Inventor

DAVID WILSON

By Clarence O'Brien, Attorney

UNITED STATES PATENT OFFICE

DAVID WILSON, OF NEW YORK, N. Y.

DOOR LATCH FOR MOTOR VEHICLES

Application filed February 14, 1931. Serial No. 515,830.

This invention relates to new and useful improvements in door latch operating means, and particularly it pertains to latch operating means for the doors of motor vehicles, carriages and the like.

Heretofore it has been the common practice to operate the latch bolt of vehicle doors by means of a knob or handle which projects from the door, and which due to its projection is a constant source of annoyance. Furthermore, these operating knobs or handles often become broken off from the door, and thereby give the same an unsightly appearance.

It is one of the objects of the present invention to provide a novel door latch operating means which does not project beyond the plane of the door, and which is normally flush with the exposed surface of that portion of the door by which the operating means is carried, thus eliminating all projecting parts, and the disadvantages thereof.

The invention will be clearly understood from the accompanying drawings illustrating the invention in its preferred form, and the following detailed description of the construction therein shown.

In the drawings,

Figure 1 is a fragmentary view in side elevation showing the door of a motor vehicle equipped with a latch operating device constructed in accordance with the present invention.

Figure 2 is a fragmentary plan view partly in section showing the bottom edge of the window opening of the door, and illustrating the position of the parts constructed in accordance with the present invention.

Figure 3 is a fragmentary vertical sectional view of a vehicle door equipped with a device in accordance with the present invention, the latch operating means being shown in full lines in the position which it occupies when the latch bolt is in door holding position, and also illustrating the manner in which the latch operating means is locked against operation, and;

Figure 4 is a detail sectional view illustrating the position of the parts when the latch bolt is in the door releasing position.

Referring more specifically to the drawings, the reference numeral 5 designates a motor vehicle body and 6 designates the door. The body is of the closed type, and the door has a window opening 7 which is adapted to be closed in the ordinary manner by a glass window pane or the like 8.

By reference to Figure 3 it will be noted that the door latch is designated 9 and the same has a latch bolt or the like 10 which is adapted to engage a keeper 11 carried by one of the stanchions or other part of the body of the car and when the latch bolt 10 is engaged with the keeper 11, the door is maintained closed. The latch may be of any conventional form, and has a latch spindle or the like 12 to which the operating knob or handle in the ordinary construction is attached, and by which it is operated. However, in the present device this operating knob or handle is eliminated and the latch bolt operating means of the present invention is attached thereto in such a manner as to operate the same in a manner to be hereinafter described.

In accordance with the present invention, the latch operating means is mounted wholly within the door and comprises a lever 15 pivotally mounted as at 16 and having a horizontal portion 17, a downwardly bent portion 18 terminating in a curved end 19. The latch spindle 12 has secured thereto a link or the like 20 and pivotally connected to this link 20 as at 21, there is a link or the like 22 which in turn is pivotally connected as at 23 to the pivoted lever 15 heretofore mentioned. Thus it will be apparent that as the lever 15 is rocked about its pivotal point, the latch spindle 12 will be rotated in its bearing, and the latch will be operated to move the latch bolt to releasing position. In that form of latch which I have selected for the illustration of my invention, the latch spindle 12 carries an operating lug or member 25 which engages the portion 26 of the latch bolt 10 and moves the same against the action of a spring 27 when the latch bolt is moved to the releasing position and which spring 27 serves to return the latch bolt 10 to its door holding

100

position in which position it is shown in Figure 3.

In its operation to move the latch bolt 10 to door releasing position, the lever 15 is depressed and for this purpose, I provide an operating member 30. This operating member 30 is set in an opening 31 in the lower edge of the window opening 7. The operating member 30 has depending skirt portions 32 which operatively engage the side walls of a wall or the like 33 in which the operating member is slidably mounted. At its upper end the operating member engages a gasket or the like 34 to provide a watertight joint between the upper edge of the operating member and the opening 31 in the edge of the window opening 7. This operating member 30 is connected to the lever 15 by means of a link 36. This link 36 is connected at its lower end to the end of the lever 19 as at 35, and at its upper end it is pivotally connected as at 37 to the operating member 30.

Thus it will be apparent that as the operating member 30 is depressed, through the medium of the link 36, the lever 15 will be rocked downwardly about its pivotal point 16, and through the medium of the link 22 and the lever 20, the spindle 12 of the latch 30 will be operated and the latch bolt 10 retracted from its door holding position.

To return the parts to their normal position and assisting the heretofore mentioned spring 27 in this operation, a spring 40 may be employed. This spring 40 is connected at one end as at 41 to a stationary point on the door, and as at 42 to the lever 15 and when the lever 15 is rocked downwardly as heretofore described, the spring 40 will be placed under sufficient tension to return the several parts to the normal position in which they are shown in Figure 3 it being assisted in this operation by the spring 27.

Means is provided to lock the operating member 30 against operation and to thereby prevent opening of the door and in the present illustration of the invention, this means comprises a bolt or the like 50 which is adapted for reception within a recess 51 in one of the skirt portions 32 of the operating member 30. This bolt may be controlled or operated by a conventional type of cylinder lock such as 55 which is preferably mounted on the exterior of the door below the bead or the like 56 thereof when such bead is present upon the door.

Thus it will be seen that when the cylinder lock 55 is operated to project its bolt 50 into the recess 51 in the skirt portion of the operating member 30, the operating member 30 cannot be depressed to move the latch bolt of the latch to door releasing position and thus the door is maintained locked.

From the foregoing, it will be apparent that the present invention provides a new

and novel mechanism for operating the latch bolt of vehicle door latches which operating means is flush with the exterior surface of that part of the door by which it is carried and which presents no projecting parts. Furthermore, it will be apparent that the present invention provides means by which the door may be locked and secured in closed position.

While the invention has been herein illustrated in what may be termed a preferred form, it is to be understood that the invention is not to be limited to the specific construction herein shown, but that it may be practiced in other forms without departing from the spirit thereof.

Having thus described the invention, what is claimed as new, and what it is desired to secure by United States Letters Patent, is:

1. In combination with a door having a latch and a window opening, a latch operating means comprising a reciprocating member mounted in one of the walls of the window opening and normally flush with the exposed face thereof, a pivoted lever, a link connected to said reciprocating member and said pivoted lever for rocking the latter about its pivotal point, means connected to and operated by said pivoted lever for moving the latch bolt to door releasing position upon operation of said reciprocating member, and means for returning said reciprocating member and said latch bolt to normal position, said last mentioned means comprising a spring connected at one end to said pivoted lever, and at its opposite end to said door.

2. In combination with a door having a latch and window opening, a latch operating means comprising a reciprocating member mounted in one of the walls of the window opening and normally occupying a position flush with the outer surface thereof, a link pivotally connected to said reciprocating member, a lever pivotally connected at one end to said link, and at its other end to the door, said lever being rockable about its second mentioned pivotal point upon depression of the reciprocating member, and latch bolt operating means pivotally connected to said pivoted lever at a point between its ends, and operable by movement of the lever, to move the latch bolt to door locking and releasing position.

3. In combination with a door having a latch and window opening, a latch operating means comprising a reciprocating member mounted in one of the walls of the window opening and normally occupying a position flush with the outer surface thereof, a link pivotally connected to said reciprocating member, a lever pivotally connected at one end to said link, and at its other end to the door, said lever being rockable about its second mentioned pivotal point upon depression of the reciprocating member, latch bolt op-

erating means pivotally connected to said pivoted lever at a point between its ends, and operable by movement of the lever, to move the latch bolt to door locking and releasing position, and means for holding said latch bolt operating means normally in latch bolt projecting position.

5 In testimony whereof I affix my signature.
DAVID WILSON.
